Primary Examiner — Cathron C Brooks*Assistant Examiner* — Sharon S Oum(74) *Attorney, Agent, or Firm* — McGarry Bair PC**(57) CLAIM**

The ornamental design for a ceiling fan motor housing, as shown and described.

DESCRIPTION

FIG. 1 is a top perspective view of a ceiling fan motor housing in the environment of a ceiling fan showing my new design;

FIG. 2 is a bottom perspective view of the ceiling fan motor housing of FIG. 1;

FIG. 3 is a front side view of the ceiling fan motor housing of FIG. 1, with the rear side view being a mirror image thereof;

FIG. 4 is a right side view of the ceiling fan motor housing of FIG. 1, with the left side view being a mirror image thereof;

FIG. 5 is a top view of the ceiling fan motor housing of FIG. 1; and,

FIG. 6 is a bottom view of the ceiling fan motor housing of FIG. 1.

Portions of the ceiling fan motor housing and the ceiling fan environment shown in broken lines form no part of the claimed design.
